WILLIAM M. STEELE, OF RIVER FOREST, AND EDWARD G. ALLEN, OF OAK PARK, ILLINOIS, ASSIGNORS TO JOHN F. JELKE COMPANY, OF CHICAGO, ILLINOIS, A CORPORATION OF ILLINOIS

CONTAINER FOR COLORING MATERIAL

Application filed October 8, 1928. Serial No. 310,969.

This invention relates to a moisture proof container, more particularly intended for containing and protecting material used for coloring oleomargarine and the like.

5 The device is particularly designed to be efficient as a container for such coloring material in fluid or powdered form, and it may be packed in a carton with the oleomargarine or other product with which it is to be used, 10 without affecting the container or its contents.

One object of the invention is to so construct the container that its parts may be reliably connected together, and to use cementing means for this purpose which will not 15 contaminate the contents.

In the drawings:

Figure 1 is a top plan view of the container embodying our invention.

Figure 2 is a vertical sectional view taken 20 on the line 2—2 of Figure 1.

That embodiment of the invention shown in the drawings comprises two plate members 3, 4, each preferably made of a single layer of cellulose, a moisture proof, transparent material which is not affected by contact with 25 the coloring material to be contained therein, nor by contact with the oleomargarine or other product with which it may be packed for marketing purposes.

30 The lower plate member 3 is formed with a relatively deep dished portion comprising a substantially flat, circular bottom wall 5 and an upwardly and outwardly inclined wall 6. Extending outwardly and downwardly from 35 the top margin of the wall 6 and integral therewith, is an annular ring 7, terminating in a marginal flange 8, which may be horizontally disposed as shown, or be slightly upturned.

40 As shown, the upper plate member 4 comprises a substantially flat, central, circular wall 9, slightly larger in diameter than the lower wall 5 so as to function as a cover for the dished portion of the lower plate 3 and 45 extends to the upper margin of the inclined wall 6. Extending outwardly and downwardly from the top wall 9, the member 4 has an annular ring 10 and flange 11 complementary to the parts 7 and 8, respectively, of 50 the member 3. The top wall 9 is in a substan-

tially horizontal plane, somewhat above those complementally formed, connected flange portions of the two plates. If the powdered coloring material is in the container in sufficient quantities, it is possible the top 9 will be slightly bulged upwardly, but when the contents of the container is a fluid, the top of the container will be substantially flat in its central portion.

55 The marginal portions of both plate members 3, 4, comprising the parts 7, 8, 10 and 11, are securely connected together after the coloring material has been placed in the member 3 by a cement indicated at 12. Preferably the cement used is ethyl lactate. Other 60 cementing means may be used, but we prefer to use one having the characteristics of ethyl lactate.

65 By forming the container members as shown, a chamber for the coloring material is 70 provided, and the connected marginal portions not only close the chamber, but are so shaped and located relative to the chamber walls that same are reinforced and protected thereby.

75 It will be understood that to make the members 3, 4, the cellulose is shaped by the use of dies to form a plurality of lower members 3, then the coloring material 13 is placed in the dished portions thereof, and another piece 80 of cellulose is placed in juxtaposition to the lower members, and, after being shaped to form the parts 10, 11 for a plurality of plates 4, is connected to the parts 7, 8 by the cement 12. Then the separate containers may be 85 cut in the octagonal form shown, or any other desired shape. Preferably a slight amount of heat is applied to the cellulose to facilitate the shaping of the plate members 3 and 4.

90 The construction described is well adapted as a container for coloring material in fluid or powdered form, because of the characteristics of the materials used therein and because of the form thereof. The arrangement 95 of the container is such that the contents are efficiently held therein while the container members are being connected together and subsequently; and the marginal portions of the container are so shaped that a maximum 100

of contacting surfaces for connection with each other is provided in a minimum of radial space.

Obviously, changes in details of construction may be made without departing from the scope of our invention, and we do not intend to be limited to the precise form shown and described, except as pointed out in the appended claims.

10 We claim as our invention:

1. A container comprising a plate having a centrally dished portion and a downwardly and outwardly inclined annular ring integral therewith, a second plate having a substantially flat central portion sufficient in area to cover the dished portion of the first plate and a downwardly and outwardly extending annular ring complementary to the ring of said first mentioned plate, and means for connecting said complementary portions together.

2. A moisture proof container comprising a bottom plate member including a substantially flat central portion and an upwardly and outwardly inclined wall whereby a dished portion is formed, and an annular downwardly and outwardly extending ring integral therewith, an upper plate member having a substantially flat central portion slightly larger in area than the flat central portion of the lower member, and a ring integral with said central portion and complementary to said first mentioned ring, and cement for connecting said annular rings together.

3. A container made of cellulose comprising a plate having a centrally dished portion and a downwardly and outwardly inclined annular ring integral therewith, a second plate having a substantially flat central portion sufficient in area to cover the dished portion of the first plate and a downwardly and outwardly extending annular ring complementary to the ring of said first mentioned plate, and a layer of ethyl lactate for connecting said complementary portions together.

4. A moisture proof container made of cellulose comprising a bottom plate member including a substantially flat central portion and an upwardly and outwardly inclined wall whereby a dished portion is formed, and an annular downwardly and outwardly extending ring integral therewith, an upper plate member having a substantially flat central portion slightly larger in area than the flat central portion of the lower member, and a ring integral with said central portion and complementary to said first mentioned ring, and a layer of ethyl lactate for connecting said annular rings together.

5. A moisture proof container made of cellulose comprising a bottom plate member having a substantially flat central portion, a wall upwardly and outwardly inclined from said central portion and an outwardly

extending ring integral therewith, and an upper plate member marginally connected to said ring member of the first plate by a layer of ethyl lactate.

In testimony that we claim the foregoing as our joint invention, we affix our signatures, this third day of October, 1928.

WILLIAM M. STEELE.
EDWARD G. ALLEN.
